[57] CLAIM

The ornamental design for a thermal indicator for vac-

uum sterilizer test packs, substantially as shown and described.

DESCRIPTION

FIG. 1 is a top plan view of a thermal indicator for vacuum sterilizer test pack showing my new design;
FIG. 2 is a side elevational view thereof;
FIG. 3 is an enlarged section taken on line 3—3 of FIG. 1;
FIG. 4 is a top plan view of the indicator after exposure in vacuum sterilizer;
FIG. 5 is a top plan view of a thermal indicator for vacuum sterilizer test pack showing a second embodiment of my new design;
FIG. 6 is a top plan view of a thermal indicator for vacuum sterilizer test pack showing a third embodiment of my new design; and
FIG. 7 is a top plan view of a thermal indicator for vacuum sterilizer test pack showing a fourth embodiment of my new design.
All embodiments are plain in bottom plan, with side and sectional views as shown in FIGS. 2 and 3.
